INVENTOR -

Eligah D. Davis
By David A. Burr

UNITED STATES PATENT OFFICE.

ELIJAH D. DAVIS, OF BROOKLYN, NEW YORK.

BORING-MACHINE.

SPECIFICATION forming part of Letters Patent No. 253,913, dated February 21, 1882.

Application filed December 15, 1881. (No model.)

To all whom it may concern:

Be it known that I, ELIJAH D. DAVIS, a resident of Brooklyn, county of Kings, and State of New York, have invented certain new and useful Improvements in Portable Drill-Tables; and I do hereby declare that the following is a full, clear, and exact description thereof, reference being had to the accompanying drawings, and to the letters of reference 5 marked thereon, making a part of this specification.

My invention is designed to facilitate the drilling of portable objects of any and all descriptions with perfect accuracy and exactness 15 of alignment at any desired angle, measured and determined with precision by means of fixed scales.

It consists in the construction of a simple compact apparatus embracing, first, a table 20 provided with adjustable clamps to hold the work, mounted upon a suitable bed-plate on an upright standard which admits of rotation upon its own axis, the table being so pivoted to the standard as to admit of being inclined at any 25 desired angle and to be secured at any desired point of its inclination; second, an arbor adapted to hold and carry a drill, and which is made to rotate in front of the table and to traverse to and from the same in bearing-blocks made 30 adjustable both as to height above and alignment with the bed-plate in standards projecting from the bed-plate, these standards being themselves capable of adjustment as to their distance from the table.

35 In the accompanying drawings, Figure 1 is a longitudinal section through my improved drill-guide and table; Fig. 2, a top view of the same, and Fig. 3 a detached plan view of the table.

40 A is the bed-plate of my device, supported upon legs *a a*, or otherwise adapted to be secured to a bench or table for support.

B is an upright standard, having a flange or collar, *b*, adapted to rest upon the bed-plate, 45 and whose lower end, projecting below said flange, passes through a slot, *c*, in the bed-plate, and is clamped and secured by means of a lock-nut, *C*, as shown in Fig. 1. By loosening the nut *C* the standard may be turned upon 50 its axis, as may be desired.

The margin of the collar *b* may be graduated

and an index-mark be fixed upon the bed-plate, so as to indicate the degree to which the standard has been moved upon its axis from a given point. I contemplate forming a hinged joint 55 in said standard, as at D, Fig. 1, to be locked by means of a nut on the hinge-pin, or by other suitable device, this joint admitting of an inclination of the standard from the perpendicular, if desired.

E is a table, centrally pivoted to the upper end of the standard by means of a pivot-plate, *e*, projecting therefrom centrally on its under side at a right angle thereto, and which passes into a slot in the upper end of the standard, a 60 pivot-pin being passed through the side of the slot to engage the standard and form a hinge upon which the table is free to tip from a horizontal to a vertical position. A set-screw, *d*, 65 serves to fix the table at any angle to which it 70 may be thus inclined, and the degree of inclination is noted by means of a scale upon the face of the pivot-plate *e* (see Fig. 1) and an index-mark on the standard.

F F are uprights or standards resting upon 75 the bed-plate A, in front of the standard B, in line therewith. These standards are provided at their lower ends with pins or bolts *ff*, adapted to pass into and project through slots or apertures and to receive nuts *f' f'*, by means of 80 which they are firmly secured. These standards F F are slotted longitudinally in both directions. (See at *w w' w' w'*, Fig. 1.) These slots intersect centrally in the standards. Bearing-blocks G G are fitted within the slots in 85 line with the bed-plate, and are secured at any elevation by means of pins or studs *HH*, projecting centrally therefrom on each side through the transverse slots *w' w'*. (See Fig. 2.) These pins serve as axes or trunnions upon which 90 the blocks may turn, (see dotted lines in Fig. 1,) and the blocks are secured, when in proper position, above the bed-plate and at the desired inclination by means of lock-nuts on the ends of the pins *HH*.

An arbor or drill-shaft, K, is journaled in the bearing-blocks, so as to rotate freely therein parallel with the bed-plate and in line with the standard B, supporting the table C. This shaft has free play longitudinally in its bearings. The 95 two standards F F are connected by means of a coupling-rod, T, extending from the one to 100

the other, and which is fixed to the one and secured to the other by a set-screw. The forward end of the drill-shaft next to the table is adapted, by means of a suitable socket or 5 clutch, L, to engage and hold any required size or character of bit or drilling-tool. Its rear end is fitted with a crank, or with a pulley, by means of which power is applied thereto to produce its rotation.

10 The table E is fitted with a disk or plate, M, rotating thereon upon a central pivot-pin, P. This plate is provided with a series of strips, N N, (see Fig. 3,) pivoted to the disk, each upon a central pin, upon which they may be turned 15 to any angle. Upon these pivoted strips N N are fitted sliding clamps R R, of substantially the form shown in the drawings, (see Figs. 1 and 2,) which are adapted to traverse back and forth upon each strip, and are secured by means of 20 a central thumb-screw or clamp-screw, Q. Each clamp may thus be fitted at a point nearer to or farther from the center of the table and at any angle with reference thereto.

The rotating plate M is itself fixed as required 25 by means of a set-screw or other suitable catch, m. The use of this rotating plate M may be dispensed with, and the strips for holding and guiding the clamps P P may be fitted on the table itself.

30 In the use of my device the work or object to be drilled is secured upon the plate M by means of the sliding adjustable clamps P P, which, from their form, their freedom to rotate upon the axis of the guide-strips N, and their 35 ready adjustment to and from the center of the table, are adapted to engage firmly any piece of work of any form whatever in proper position for drilling. The work being secured upon the plate M, the plate is then rotated upon 40 its axis, the table C carrying the plate tipped upon its axis and the standard B carrying the table rotated upon its axis until the work is brought exactly into proper position and alignment with reference to the drilling-tool fixed in 45 the arbor K required to produce a bore in the desired direction. The plate M, table C, and standard B are then fixed and secured immovably by means of their set-screws. The drilling-tool carried by the arbor K is also suitably 50 adjusted in height by moving and setting the bearing-blocks G G higher or lower in the slotted standards F F, and is brought in proper prox-

imity to the work by moving said standards in the bed-plate nearer to or farther from the standard B. If required, the inclination of the arbor itself may be varied by sliding one of its bearing-blocks up or down independently of the other, such an adjustment being permitted by the pivot-pins H H, upon which the blocks may turn, as shown in dotted lines, Fig. 1. 55 When the adjustments are all complete the drilling is rapidly performed by the rotation of the arbor and drill, either by hand or by power. Cams or other forms of catches may be substituted for the nuts and set-screws in fixing the 60 clamps and other movable parts of my device. 65

A single bearing-block or standard of sufficient depth to afford a long bearing for the arbor may be used as an equivalent for the two blocks F F, arranged as above described. 70

What I claim as new, and desire to secure by Letters Patent, is—

1. The combination, with a suitable bed-plate, A, and with an arbor, K, adapted to receive and carry a drilling-tool and to traverse longitudinally and rotate freely in adjustable bearings over said bed-plate, of a table, C, for holding the work to be drilled, supported upon a standard, B, upon the bed-plate, and adjusted to tip upon and to turn with said standard to any desired angle in front of the drill, substantially in the manner and for the purpose herein set forth. 75

2. The combination, with an arbor or drill-shaft, K, and with a drill-table, C, adapted to tip and to turn to any angle with the drill, of 80 a plate, M, pivoted centrally to said table to rotate thereon, and fitted with retaining or clamping devices for holding the work thereon, substantially in the manner and for the purpose herein set forth. 85

3. The combination, with the drill-table C and drill-arbor K, of the pivoted strips N N and the sliding clamps R R, traversing upon said strips, adapted for holding the work in position for the drill, substantially in the manner and for 90 the purpose herein set forth. 95

In testimony whereof I have signed my name to this specification in the presence of two subscribing witnesses.

ELIJAH D. DAVIS.
